COMBINATION BREATHER PIPE AND OIL CAN OPENER

Filed April 2, 1935

FIG. 2

FIG. 4

UNITED STATES PATENT OFFICE

2,034,958

COMBINATION BREATHER PIPE AND OIL
CAN OPENERHenry F. Plaster, Socorro, N. Mex., assignor of
forty-nine per cent to Alvan S. Fair, Socorro,
N. Mex.

Application April 2, 1935, Serial No. 14,337

2 Claims. (Cl. 184—105)

This invention relates to devices for supplying oil to crank cases of automobile engines, and particularly to those devices which in practice are associated with the breather pipe so as to permit the oil to flow from a can or other container through the breather pipe into the crank case.

When a motorist buys oil at a service station it is dispensed usually, in order to avoid spilling, through a quart measure, whether the oil be in bulk or canned oil. A great many stations use the "swing spout" measure which, when the spout is up after being used, will have at least two ounces of oil left in the measure. This settles in the opening of the spout and then contaminates or mixes with oil which is being subsequently dispensed, so that sometimes an expensive grade of oil is contaminated by an inferior grade and sometimes an inferior grade of oil becomes mixed slightly with a superior grade of oil. Furthermore, where the attendant opens a sealed can of oil and pours the oil into a dispensing can, there is a chance of the attendant "switching" the oil and, as a matter of fact, dispensing an inferior grade of oil for the good grade, for which he has been paid.

The general object of my invention is to provide an oil can opening means which also constitutes an extension of the breather pipe of the engine or which is disposed around or within the breather pipe and which extends upwardly from the breather pipe to any desired height and is adapted to receive the lower end of a can of oil.

A further object, in this connection, is to provide a puncturing means mounted upon the bottom of that portion of the device which receives the can of oil so that when the attendant or owner inverts the can of oil within the holder and forces the can downward, the can will be punctured and the contents will flow downward through the breather pipe into the crank case, the can remaining in this position until it is entirely drained of oil.

A further object is to provide means for puncturing the top of the can to permit the inlet of air so that the oil may flow and, in this connection, to provide a top for the can holder so designed that it constitutes the top of the breather pipe as it were, and permits the inlet of air under normal circumstances, this cap being provided with a spike whereby the top of the can may be punctured.

A further object is to provide a device of this character which is so designed as to fit any automobile engine and which will permit a round sealed quart can of oil to be inserted readily and

as readily removed without chance of the operator soiling his fingers.

Other objects will appear in the course of the following description.

My invention is illustrated in the accompanying drawing wherein:

Figure 1 is a vertical sectional view through a can holder opener and breather pipe extension constructed in accordance with my invention, a portion of the breather pipe being shown in section.

Figure 2 is a section at right angles to the section shown in Figure 1, this view showing a can of oil disposed within the holder and the cap in place to puncture the top of the can of oil.

Figure 3 is a plan view of the holder, the cap and can being removed.

Figure 4 is an elevation showing a slightly modified form of can holder and breather pipe extension.

Referring to this drawing, 10 designates a cylindrical can holder and breather pipe extension which is of metal or any other suitable material and which is formed with a conical or downwardly and centrally inclined bottom 11 and terminates at its lower end in a downwardly extending neck 12, which is adapted to be inserted within the upper end of a breather pipe 13. At the lower end of the conical portion 11 there is attached to the wall of the portion 12 a cutter 14 which is of stiff sheet metal. This has a portion 15 which conforms in curvature to the curvature of the neck 12 for a portion of the width of the cutter and it is formed to provide two inwardly curved wings 16 which extend across the opening 17 leading from the body of the can holder into the neck 12. The upper end of the cutter is upwardly and medially inclined at 18 from each wing 16 so as to form a sharp-edged and sharp pointed prong so that when a can of oil is disposed within the holder 10 and forced downward, this cutter will cut a curved opening within the top of the can. The resistance offered to the cutting of the can will tend to force the metal cut out by the edges 17 upward so that oil will readily flow from the can through the spout formed by the portion 14 and the wings 16, this oil discharging through the openings 16 and neck 12 into the breather pipe 13 and so into the crank case in the usual and ordinary manner.

For the purpose of puncturing the top of the can to permit the inlet of air, I provide a cap or cover designated generally 18 and shown in Figure 2, as in place upon the top of the can. This cover, when a can has been drained of its oil, rests

upon the upper edge of the cylindrical can holder 10. This cylindrical can holder when the can has been drained of oil and removed, constitutes an extension of the breather pipe 13 and the cap 18 constitutes then a breather pipe cap. To this end, this cap is formed with the inner circular wall 19 which extends upward to the top of the cap and the top of the cap is carried downward and outward to form a skirt 20, there being openings 21 through this wall 19 into the space defined by or overhung by the skirt 20. Thus air can pass up from beneath the skirt 20, pass through the openings 21 and pass downward through the breather pipe. The cap 18 may be formed to filter the air thus passing into the breather pipe and to that end may be provided with a loose packing of copper wool or the like, though I do not wish to be limited to this.

For the purpose of puncturing the can, I have provided the cap 18 with a spike 22 which is affixed to the cover and extends downward there-through so that when a can is inserted within the holder 10 and the cap 18 is mounted on top of the can, as shown in Figure 2, and forcibly pressed downward, the spike 22 will puncture the top of the can. This action, after the can top is punctured, will force the can downward upon the can cutter 14. When this has been done, the cap 18 is removed and then, of course, oil will flow downward through the punctured bottom of the can into the breather pipe. After the can has been entirely drained of oil, the can may be removed from the holder and the cap put in place upon the top of the holder whereupon it acts like the usual cap to a breather pipe.

Inasmuch as the bottom of the usual oil can is flat, the puncture at the center of the can will not drain off all the oil, and for the purpose of saving this oil, which does not drain out through the central opening, I provide a spike or prong 23 which extends upward from the upper end of the conical portion 11 closely adjacent the side wall. When the can is forced downward against the cutter 14, the bottom of the can will also be punctured by the spike 23, but no oil will flow out of this puncture because the spike 23 will act as a plug. If however, there should be some slight leakage of oil, this will run down the inclined bottom 11 into the opening 16. Now when the can is removed, if there is any oil left on the bottom of the can, the can is tilted upward so that the puncture formed by the spike 23 is at the lowest portion of the can and the oil may then drain out of the can into the member 10 and will flow down into the breather pipe. Thus it is possible with my structure to secure practically every particle of oil that there is in the can, and without any danger of the oil being contaminated or adulterated, or a poor grade of oil being substituted for a good grade.

In Figure 4, I have shown a slight modification of the neck 12 in which the neck instead of extending straight downward, extends laterally outward, as at 12a, and then downward, as at 12b. This modification permits my device to be used on those cars in which it is necessary to offset the can holder from the breather pipe in order to get room for the can holder.

It will be seen that I have provided means adapted to be detachably mounted upon the ordinary breather pipe whereby a can of oil may be held while it is draining and whereby the bottom

of the can and the top of the can too may be punctured to permit the discharge of oil.

It will be seen that the oil can holder which constitutes an extension of the breather pipe is covered when not in use, thus keeping out dirt and grit. The can may be left to drain within the holder without any attention and without any danger of falling and in the meanwhile, other car services may be performed. The device eliminates the likelihood of spilling oil on fenders, motors and other parts, and while it is particularly adapted for canned oil, yet it is also perfectly capable of being used for bulk oil as it constitutes a funnel or hopper-shaped receiving end for the breather pipe.

With my construction, it will be seen that the oil will have plenty of room to back up should air in the oil chamber of the motor cause it to flow more slowly down the breather pipe than it does out of the can. This is permitted by the space between the bottom of the can, which rests upon the holder at the upper end of the inclined portion 11, and the bottom of the holder. The neck may, of course, be constructed to fit any standard size of breather pipe and the holder itself to receive the lower end of any size can.

While I have illustrated the holder as cylindrical in form, it is obvious that it might be rectangular in plan, without departing from the spirit of the invention.

While I have illustrated the cutter 14 as being made separate from the neck 12, it is to be understood that this cutter 14 might be integral with the wall 12 or 11, and that I do not wish to be limited to the particular construction illustrated, except as defined in the claims.

What is claimed is:—

1. An oil can holder for automobiles including a body adapted to receive the lower end of an oil can, the lower end of the body extending downward and centrally, the lower end of the downwardly and centrally extending portion having a downwardly extending neck adapted to be inserted within the oil pipe of a motor, the body having a diameter such that the oil can will rest upon the upper end of the downwardly and centrally inclined portion, and a cutter extending straight upward from the neck at the junction of the neck with the downwardly inclined portion, the cutter being disposed substantially centrally with relation to the body and being approximately circular in cross-section and having a sharp upper end, the cutter for the greater portion of its width conforming to the curvature of the neck and the side margins of the cutter being bent inward to extend partly across the opening of the neck.

2. An oil can holder including a body portion adapted to receive an oil can, the lower end of the body portion being downwardly and centrally tapered and terminating in a neck portion adapted to extend downward into the oil intake of an engine crank case, the lower end of the downwardly tapering portion being provided with an upwardly projecting cutter formed to cut an opening in the bottom of the oil can at the center thereof when the can is forced downward into the holder, the upper end of the downwardly tapering portion of the holder being provided with an upwardly projecting spike located closely adjacent the wall of the holder whereby to puncture the bottom of the can adjacent said wall.
